(57) CLAIM

The ornamental design for a bath towel with pockets, as shown and described.

DESCRIPTION

FIG. 1 is a front orthogonal view of a towel with pockets showing my new design;

FIG. 2 is a rear orthogonal view thereof;

FIG. 3 is a front view thereof shown hanging; and,

FIG. 4 is a right side view thereof.
